DESIGN FOR A HANDLE FOR SAUCE PANS

Alfred F. Ramsthal, West Bend, Wis., assignor to West Bend Aluminum Co., West Bend, Wis.,
a corporation of Wisconsin

Application September 30, 1939, Serial No. 87,452

Term of patent 14 years

To whom it may concern:

Be it known that I, Alfred F. Ramsthal, a citizen of the United States, residing at West Bend, in the county of Washington and State of Wisconsin, have invented a new, original, and ornamental Design for a Handle for Sauce Pans, of which the following is a specification, reference being had to the accompanying drawing forming a part thereof, and in which:

I claim:

The ornamental design for a handle for sauce pans, as shown.

ALFRED F. RAMSTHAL.
